UNITED STATES PATENT OFFICE.

HARRY LIEBECK, OF PHILADELPHIA, PENNSYLVANIA, ASSIGNOR TO SCOTT PAPER COMPANY, A CORPORATION OF PENNSYLVANIA.

PAPER-SERVING APPARATUS.

1,101,862.

Specification of Letters Patent. Patented June 30, 1914.

Application filed September 21, 1910. Serial No. 582,996.

To all whom it may concern:

Be it known that I, HARRY LIEBECK, a citizen of the United States, and resident of the city and county of Philadelphia, State of Pennsylvania, have invented an Improvement in Paper-Serving Apparatus, of which the following is a specification.

It is the object of this invention to provide a simple and efficient apparatus for serving paper, such as toilet-paper or toweling, from a roll, and to overcome the difficulties heretofore existing in apparatus of the kind owing to the tearing and wasting of the paper.

15 In the drawings: Figure 1 is a front elevation of a paper roll-holder and delivering device embodying the invention; Fig. 2 is a plan view; Fig. 3 is a vertical sectional view on the line A—A of Fig. 1; and Fig. 4 is an 20 end elevation.

a is a base-plate adapted to be secured to the wall.

b, *b* are bracket-arms carried by the base-plate and provided at their outer ends with 25 bearings for the rotary mandrel *d* upon which the roll of paper *e* is placed. As shown, one of the bearings is formed by a cylindrical boss *f* on which one of the ends of the cylindrical mandrel is slipped, and the 30 other bearing is formed by a cylindrical socket *f'*, which receives the slightly enlarged cylindrical head *g* of the mandrel. The faces of the boss *f* and head *g* are closed by webs *h* *h'* respectively, through which extends the shaft *j*. The outer end of the shaft *j* is provided with a retaining head *i* which lies on the inside of the web *h* of the bearing-boss *f*, and the shaft is provided with a non-circular portion *k* which fits a complementary hole in the web *h'* of the head *g* of the mandrel. A spring *m* between the web *h'* and a nut *n* on the shaft—the tension of which may be regulated by the adjustment of the nut—retains the shaft in place with 45 the retaining head *i* bearing on the web *h* of the bearing-boss. The outer end of the shaft *j* projects beyond the arm *b* at that end and is provided with a knob or handle *o* by which the shaft *j* and, with it the mandrel *d* and roll of paper *e*, may be rotated.

The roll of paper is fitted tightly on the mandrel so as to be rotated by it, and for this purpose the mandrel may be provided with retaining projections *p p*. The base *a*, 50 arms *b* and mandrel *d* are all preferably

formed of stamped sheet metal. This form of the device is particularly adapted for rolls of toilet-paper; the person using the apparatus turns the roll by the operation of the handle *o* to unroll the paper, which is 60 then torn off. This rotation of the roll by means of a shaft operated by a handle enables any length of paper to be unrolled, without putting any strain upon the paper and without any possibility of tearing it. 65 When the paper is unrolled by a direct pull upon it, as is now usual, the paper is liable to break off at the perforations, before the desired amount is unwound, or to tear apart between the perforations. This is particularly liable to occur if any substantial tension is placed upon the roll to resist its free 70 rotation upon its mandrel, and unless there is a substantial tension, or resistance to rotation, the roll will rotate so freely with a 75 hard pull, that too much paper will be unrolled, resulting in great waste, or, if the paper breaks off with a loose end, while the roll is rotating, the loose end may be carried up and become snarled in the fixture. The 80 adjustment of the spring *m* by the nut *n* enables the tension on the mandrel to be so regulated that, while the mandrel may be rotated with facility, there may be sufficient 85 resistance to prevent the paper being unrolled to any substantial further extent when being torn off.

What I claim is as follows:

1. In paper-serving apparatus, the combination of supporting arms provided with 90 bearings, a hollow sheet metal tube journaled at its ends in said supporting arms and constituting a hollow rotary mandrel adapted to support a roll of paper, a shaft extending through said mandrel, projecting 95 at one end through one of the supporting arms, and provided on said projecting end with an operating handle, said shaft being operatively connected with the mandrel.

2. In paper-serving apparatus, the combination of supporting arms provided with 100 bearings, a hollow sheet metal tube journaled at its ends in said supporting arms and constituting a hollow rotary mandrel adapted to support a roll of paper, a shaft 105 extending through said mandrel, projecting at one end through one of the supporting arms, and provided on said projecting end with an operating handle, said shaft being operatively connected with the mandrel, 110

2
and a spring acting on said mandrel and imposing frictional resistance between the mandrel and its bearings.

3. In paper serving apparatus, the combination of two supporting arms *b*, *b*, one provided with a boss *f* and the other with a socket *f'*, a hollow sheet metal tube having one end journaled on the boss and the other journaled within the socket, said tube constituting a mandrel adapted to carry a roll of paper, and a handle connected with said mandrel for manually operating the same, and a spring for regulating the tension between said mandrel and its bearings.

4. In paper serving apparatus, the combination of two supporting arms *b*, *b*, one provided with a boss *f* having a web *h* and the other with a socket *f'*, a hollow sheet metal tube having one end journaled on the boss and the other journaled within the socket, said tube constituting a mandrel adapted to carry a roll of paper and being provided at one end with a web *h'*, a shaft extending through said tube and operatively connected with said webs *h*, *h'*, a handle connected with said shaft for manually operating the same, and a spring between said shaft and mandrel imposing frictional resistance between the mandrel and its bearings.

connected with said shaft for manually operating the same.

5. In paper serving apparatus, the combination of two supporting arms *b*, *b*, one provided with a boss *f* having a web *h* and the other with a socket *f'*, a hollow sheet metal tube having one end journaled on the boss and the other journaled within the socket, said tube constituting a mandrel adapted to carry a roll of paper and being provided at one end with a web *h'*, a shaft extending through said tube and operatively connected with said webs *h*, *h'*, a handle connected with said shaft for manually operating the same, and a spring between said shaft and mandrel imposing frictional resistance between the mandrel and its bearings.

In testimony of which invention, I hereunto set my hand.

HARRY LIEBECK.
